(57) **CLAIM**

The ornamental design for a key finial, as shown.

DESCRIPTION

FIG. 1 shows a perspective view of a key finial incorporating the design;

FIG. 2 shows a right side elevational view of the key finial shown in FIG. 1;

FIG. 3 shows a front elevational view of the key finial shown in FIG. 1, the rear elevational view being identical;

FIG. 4 shows a top plan view of the key finial shown in FIG. 1, the bottom plan view being a mirror image thereof; and,

FIG. 5 shows a left side elevational view of the key finial shown in FIG. 1.
